UNITED STATES PATENT OFFICE.

JOSEPH L. ROHR, OF LEWISTON, MAINE.

CAR-DOOR LOCK.

1,158,720.

Specification of Letters Patent.

Patented Nov. 2, 1915.

Application filed July 2, 1915. Serial No. 37,742.

To all whom it may concern:

Be it known that I, JOSEPH L. ROHR, a citizen of the United States, residing at Lewiston, in the county of Androscoggin and State of Maine, have invented new and useful Improvements in Car-Door Locks, of which the following is a specification.

This invention relates to improvements in car door locks, the object being to provide a device of this character of novel construction including among other features a frangible seal adapted to be broken to effect a release of the lock, with a view of preventing the door from being opened by unauthorized persons without giving evidence of the fact.

Another object of importance resides in the provision of a device of this character, wherein the above mentioned seal in place forms a part of the lock mechanism, thereby preventing the door from being locked subsequent to the breaking of the seal, or until a new seal is operatively associated with the lock mechanism.

Other objects will appear as the nature of the invention is better understood from the following description, wherein the construction, combination and arrangement of parts is fully set forth.

In the drawings forming part of this application like numerals of reference indicate similar parts in the several views and wherein:—Figure 1 is a view showing the application of the lock. Fig. 2 is a longitudinal vertical sectional view through the lock showing the operative position of parts. Fig. 3 is a similar view showing the position of parts subsequent to the breaking of the seal. Fig. 4 is a vertical transverse sectional view. Fig. 5 is a horizontal longitudinal sectional view. Fig. 6 is a front end view.

Referring more particularly to the drawings, the device forming the subject matter of my invention comprises an elongated casing A constructed from any suitable material and including a bottom 5, top 6, end walls 7, and side walls 8, the casing being adapted to be secured to the body of the car B at one side of the door opening therein by means of suitable fastening elements 9 extending through one of the side walls 8. The front end wall 7 terminates short of the bottom 5 to provide an opening 10 through which the hasp 11 carried by the

door C enters the casing A and is locked 55 therein in the manner to be presently described. Projecting from the door C is a pin 12 adapted to support the hasp 11 in a line with the opening 10 whereby the hasp will be directed through said opening into 60 the casing when the door C is moved to closed position.

Mounted between the side walls 8 in a line with the longitudinal center of the casing A, and adjacent the rear end wall 7 thereof, is 65 a bearing 13 upon which the lever 14 is mounted for pivotal movement, the forward end of which has associated therewith, by means of a slot and pin connection 15, a plunger 16, the latter having the cylindrical 70 upper portion 17 slidably mounted through a suitable opening in the top 6 of the casing and formed with a knob 18, while the lower portion of the plunger is relatively broad and flat as indicated at 19 having its lower 75 edge beveled as at 20. As above stated, the plunger is mounted for reciprocatory movement through the top of the casing, and has its lower portion movable through the guide 21, the latter comprising oppositely disposed 80 substantially U-shaped strips 22 terminally connected in spaced relation to the opposite side walls 8 of the casing in any suitable manner.

Arranged within the casing immediately 85 below the guide 21 is a hopper 23 adapted to support a frangible seal element 24, which latter is adapted to be inserted within the casing through an elongated transverse slot 25 in the front end wall 7 of the casing, the 90 lower edge of the slot being disposed flush with the upper surface of the hopper as clearly shown in Fig. 2. The opposite sides of the hopper terminate to provide reversely disposed flanges 26 and 27 respectively, the 95 flange 26 depending from one side of the hopper and being secured to the front wall of the casing in any suitable manner, while the flange 27 rises from the opposite side of the hopper and provides an abutment for 100 the seal 24 to limit the insertion of the latter within the casing. The flange 27 terminates to provide the attaching lugs 28 adapted to be secured to the opposite side walls 8 of the casing in any suitable manner.

Now it will be noted that when the frangible element 24 is positioned within the casing, the element is engaged by the plunger

16, thereby forming a support for the latter, and the plunger by reason of its association with the lever in turn holds the forward end of the lever normally in elevated position, 5 while the opposite end of the lever is maintained in close proximity to the bottom 5. The opposite end of the lever is formed with a depending offset portion 29 having its under face suitably recessed as at 30 for the 10 reception of a normally projected spring pressed keeper 31, which latter by reason of the position of the lever 14 is disposed in the path of movement of the hasp 11, whereby when the hasp is inserted within the casing, the beveled portion 32 of the keeper is 15 engaged by the forward end of the hasp, thereby elevating the keeper against the tension of the spring 33, which latter operates to project the keeper into a suitable recess 20 34 in the upper face of the hasp when the latter is brought below the keeper upon limit of the movement of the hasp within the casing, thereby effectively locking the hasp within the casing as well as the door in 25 closed position. In this position of parts a flange 35 formed upon the hasp 11 bears against the front end wall 7 of the casing and closes the transverse slot 25 therein, whereby access to the frangible seal 24 is 30 prohibited and the same wholly concealed from view. Manifestly in this position of the parts the door cannot be opened until the keeper 31 is moved out of engagement with the hasp 11, this being accomplished 35 by depressing the plunger 16 and thereby rocking the lever upon its bearing 13. During this operation the frangible seal 24 is broken by the plunger 16 and the broken particles of glass or other material from 40 which the seal is constructed are discharged from the casing through the hopper 23 and the openings 36 and 37 in the hasp and bottom 5 of the casing respectively, the opening 36 in the hasp being brought into alignment 45 with the opening 37 in the bottom of the casing upon initial association of the parts. Subsequent to the breaking of the seal 24 the forward end of the lever together with the plunger 16 assume the position illustrated in Fig. 3 and are held in this position 50 under the influence of the spring 38 thereby elevating the opposite end of the lever and permitting the door to be opened thereby withdrawing the hasp from the casing. In 55 this position of parts the plunger closes both the transverse slot 25 and the opening 10 in the front wall of the casing so that the hasp 11 cannot be inserted within the casing and locked therein until a new seal is operatively 60 positioned upon the hopper 23. The lock is very simple in its construction, and yet durable and easily manipulated in the manner hereinabove described.

It is believed that from the foregoing description the nature and advantages of the

invention will be thoroughly understood without requiring a more extended explanation and therefore the same has been omitted.

What is claimed is:—

1. A lock comprising a casing, a hasp adapted to enter the casing through one end thereof, a pivoted lever arranged within the casing, a frangible element supporting the lever in operative position for locking engagement with the hasp, means for destroying said element to effect a release of said lever, and means for holding said lever in inoperative position subsequent to the release thereof. 75

2. A lock comprising a casing, a hasp adapted to enter the casing through one end thereof, a pivoted lever arranged within the casing, and a frangible element supporting said lever in operative position for locking engagement with said hasp. 80

3. A lock comprising a casing, a hasp adapted to enter said casing through one end thereof, a lever pivotally mounted within the casing, a frangible element supporting said lever in operative position for locking engagement with said hasp, and a plunger associated with the lever for destroying said element to effect a release of said lever. 90

4. A lock comprising a casing, a hasp adapted to enter the casing through one end thereof, a lever pivotally mounted within said casing, a plunger associated with said lever and projecting from said casing, a guide for said plunger, a frangible element arranged within said casing below said guide and forming a support for said plunger whereby said plunger is held in operative position for engagement with said hasp, and said plunger being adapted to destroy said 100 frangible element to effect a release of said lever. 105

5. A lock comprising a casing, a hasp adapted to enter the casing through one end wall thereof, said wall having a transverse 110 slot therein, a lever pivotally mounted within the casing, a plunger associated with said lever, a frangible element adapted to be inserted within the casing through said slot and supported below said plunger, said element forming a support for said plunger whereby said lever is held in operative position for engagement with said hasp, means for closing said slot, and said plunger being adapted to destroy said frangible element to release said lever. 115 120

6. A lock comprising a casing, a hasp adapted to enter the casing through one end wall thereof, said wall having a transverse slot therein, a lever pivotally mounted within the casing, a plunger associated with said lever, a frangible element adapted to be inserted within the casing through said slot and supported below said plunger, said element forming a support for said plunger 125 130

whereby said lever is held in operative position for engagement with the hasp, and said hasp being so formed to close said slot when arranged within the casing.

5 7. A lock comprising a casing, a hasp adapted to enter the casing through one end wall thereof, said end wall having a transverse slot therein, a lever pivotally mounted within the casing, a frangible element adapted to be inserted within the casing through said slot, a support for said element, a plunger associated with said lever for engagement with said element whereby said lever is held in operative position for 15 engagement with the hasp, a flange on said hasp for closing the slot in the front wall of the casing, and said plunger being adapted to destroy the frangible element to a release of the lever.

20 8. A lock comprising a casing, a hasp adapted to enter said casing through one end thereof and having an opening for reg-

istry with an opening in the bottom of said casing, a hopper arranged within the casing in a line with said openings, a lever pivotally mounted in the casing, a plunger associated with said lever, a frangible element insertible through a slot in the casing and supported upon said hopper, and forming a support for said plunger whereby the lever 25 is held in operative position for engagement with said hasp, and said plunger being adapted to break said element to a release of said lever, whereupon the broken particles of said element are discharged from 30 the casing through the hopper and said openings.

In testimony whereof I affix my signature in presence of two witnesses.

JOSEPH L. ROHR.
